UNITED STATES PATENT OFFICE.

JOHAN OLSEN NYGAARD, OF CHRISTIANIA, NORWAY.

HORSESHOE-CALK.

1,391,490.

Specification of Letters Patent. Patented Sept. 20, 1921.

Application filed March 23, 1920. Serial No. 368,183.

To all whom it may concern:

Be it known that I, JOHAN OLSEN NYGAARD, a subject of the King of Norway, residing at Christiania, Norway, have invented certain new and useful Improvements in Horseshoe-Calks (for which I have filed an application in Norway Sept. 20, 1918, application No. 14,441); and I do hereby declare the following to be a full, clear, and exact description of the invention, such as will enable others skilled in the art to which it appertains to make and use the same, reference being had to the accompanying drawings, and to letters of reference 15 marked thereon, which form a part of this specification.

The present invention relates to horseshoes and has for its object a frost nail or calk, which may easily be fastened in the 20 horseshoe, and which is securely held in position without loosening.

According to the invention the frost nail is fastened in a corresponding boring or recess in the horseshoe by means of a wedge 25 member, the wedging action of which acts in the longitudinal direction of the horseshoe, *i. e.*, parallel to the direction of movement.

The frost nail may suitably consist of two 30 parts between the adjacent surfaces of which the wedge is driven after the parts have been placed in the horseshoe, said adjacent surfaces being perpendicular to the direction of movement. The frost nail may even 35 consist of one piece, the wedge being driven in between one end surface of this piece and the adjacent surface of the bore into which the nail is fitted. It is preferred to let the wedge project a little below the surface of 40 the frost nail, so that the wedge is constantly hammered into its place. The wedge member may also suitably be manufactured from harder material than the frost nail itself, so that it will always project outside the frost 45 nail as the same is gradually worn off.

In the drawings Figure 1 is a longitudi-

nal section through one form of the invention.

Fig. 2 is a front view of the same, and Fig. 3 illustrates the same as seen from 50 below.

Fig. 4 is a longitudinal section through another form of the invention.

Fig. 5 is a front view of the same, and Fig. 6 illustrates the same as seen from 55 below.

In Fig. 1 *a* is a frost nail or calk slightly dovetailed as indicated at *g* which is fitted into a hole in the horseshoe *c* fastened to the hoof *d*. A wedge *b* is driven in between the 60 end surface of nail *a* and the adjacent surface of its fastening hole. As it will be seen the wedge surfaces are perpendicular to the direction of movement, which is indicated by the arrow in Fig. 3. The wedge is provided with a hole or recess *f* for facilitating the extraction of the same.

In Fig. 4 the nail or calk consists of two parts *a*, *a'*, the wedge *b* being driven in between the same. The wedge is provided 70 with projections *e* at both sides serving to facilitate its extraction.

Claim:

A horseshoe having a cavity formed therein, a calk formed of two parts each having 75 a dovetailed tenon to conform to the walls of the cavity, the adjacent opposing surfaces of the two parts being perpendicular to the direction of movement, and a wedge interposed between said surfaces, the force of 80 said wedge acting in the longitudinal direction and parallel to the direction of movement, said wedge having lateral projections extending beyond the sides of the calk to facilitate extraction of the wedge.

In testimony that I claim the foregoing as my invention, I have signed my name in presence of two subscribing witnesses.

JOHAN OLSEN NYGAARD.

Witnesses:
